UNITED STATES PATENT OFFICE.

JUSTUS C. GOOSMANN, OF PEORIA, ILLINOIS.

HEAT-EXCHANGING APPARATUS.

Application filed August 24, 1921. Serial No. 494,762.

To all whom it may concern:

Be it known that I, JUSTUS C. GOOSMANN, a citizen of the United States, residing at Peoria, in the county of Peoria and State of Illinois, have invented certain new and useful Improvements in Heat-Exchanging Apparatus, of which the following is a specification.

This invention relates in general to heat exchanging apparatus, and more particularly to an apparatus for transferring heat from one medium to another. While my invention is capable of use for many purposes, it is particularly adapted in the form herein shown for use in refrigerating systems as a condenser, and it may be also used in such systems as a brine cooler if desired.

One of the primary objects of this invention is to provide an apparatus of the character indicated which will be efficient in operation, and with this end in view, it is so designed that the fluid to be cooled will be distributed over the cooling coils so as to facilitate and expedite the exchange of heat.

Another purpose is to so construct and arrange the coils that a large number of feet of cooling surface can be secured in a relatively small chamber, thus enabling the attainment of large capacity in an apparatus of relatively small dimensions.

Another object of the invention is to provide an apparatus which will be strong and durable and not subject to leakage under pressure, but which can be readily disassembled to permit access to the coils when desirable.

A further object is to provide an apparatus which will be simple in construction and economical to manufacture, one which will occupy but a small amount of space in proportion to its capacity, and one which will be durable and satisfactory in use.

Other objects and many of the advantages of my invention should be readily appreciated as the same becomes better understood by reference to the following description, when considered in connection with the accompanying drawings.

Referring to the drawings:

Fig. 1 is a vertical sectional view through an apparatus embodying my invention; and

Fig. 2 is an end view of the coils.

On the drawings, reference character 3 indicates generally a cylindrical casing forming a chamber, in which the cooling coils

and other apparatus, are disposed. The lower end of this casing is interiorly threaded to accommodate a plug 4 forming the bottom of the chamber, and leakage around the plug is prevented by filling in the groove between the bottom of the casing and the plug with hard solder 5. The lower end of the casing is strengthened by a heavy ring 6 which is shrunk onto the casing, and the whole structure is mounted in a suitable standard or base 7, comprising an upwardly extending split flange 8 adapted to surround the casing, and in which the casing is clamped by bolts 9.

The bottom plug 4 is provided with passages 11 and 12, forming the inlet and outlet to the chamber. When the apparatus is used as a condenser, the fluid (such as carbonic acid gas) which is delivered under pressure from a compressor, a fragment of which is indicated by reference character 10, is conducted through a pipe 13 to the passage 11 from which it is delivered into the chamber near the top thereof by a vertically disposed pipe 14. The liquid accumulating in the bottom of the chamber enters the passage 12 through a radially perforated pipe 15 projecting a limited distance into the chamber and is delivered to the expansion coils or other point of use through a delivery pipe 16.

The bottom plug 4 is also provided with a centrally disposed opening through which the pipe 17 projects. The upper end of the pipe is connected with the coils as will be later explained, and the lower end has threaded thereon a nut or ring 18. Leakage around the pipe 17 is precluded by a packing ring 19 preferably made of type metal. A hollow head 21 is adapted to surround the nut 18, and leakage between the head and the nut is guarded against by a packing ring 22 preferably of vulcanized fibre. A plurality of bolts 23 passed through the head and threaded into tapped openings 24 in the bottom 4 are utilized to draw the head toward the bottom, thus compressing the packing rings 19 and 22, so as to insure leak proof joints at the bottom of the apparatus.

The cooling liquid, such as water, for instance, in a refrigerating system is delivered to the bottom of the apparatus from a supply pipe 25 which is connected through an elbow 26 with the head 21. The liquid is supplied to this pipe from any suitable source through a pipe 20 and has connected

thereto a discharge pipe 27 equipped with a shut off valve 28 and in normal operation of the apparatus the valve 29 in an extension of pipe 25 is opened and valve 28 is closed to insure flow of the cooling liquid upwardly into the apparatus.

The upper end of the pipe 17 is connected with a header 30, best shown in Fig. 2, and one end of this header is directly connected with the end of a coil 31 while the opposite end is branched, providing the oppositely extending branches 32 and 33 which are respectively connected with the coils 34 and 35. It will thus be apparent that the cooling liquid is supplied through the header to three coils, which are arranged within the casing 3. In order to insure a substantially equal flow of fluid through each of these coils, it is necessary that they be of substantially the same length, and in order to accomplish this result, two of the coils each comprise a large and a small portion. Referring now to the drawings, it will be observed that the coil 34 which emanates from the branch 32, is of uniform diameter throughout its length and is interposed between the coils 31 and 35 in the casing. Coil 31 is of sufficiently reduced diameter throughout its lower portion to be disposed inside the coil 34, but its upper portion is considerably larger in diameter so as to be disposed outside the coil 34. Coil 35 on the other hand has a lower portion sufficiently large to be disposed outside the coil 34 but its upper portion is reduced in diameter so as to be disposed within the coil 34. With this construction and arrangement of the coils, the aggregate lineal length of the three coils is substantially equal so that the cooling fluid will flow through all of the coils without tendency to short circuit through one of them, as would be the case if one coil were shorter than the others.

At their upper ends the coils are connected through a header 36, similar in construction to the lower header 30 and delivery from the header is effected through a pipe 37 to a delivery pipe 38. The packings and connections between pipes 37 and 38 are substantially similar in structure to those employed at the bottom of the apparatus, which have been previously explained. The top of the casing 3 is closed by a cap 39 grooved at 41 to receive the upper edge of the casing, which is forced against a copper gasket 40 when the cap is threaded onto the casing as shown in Fig. 1. To further ensure against leakage a packing ring 42 is disposed in a suitable seat between the casing and the lower edge of the cap and a compression ring 43 is adapted to compress this packing ring when the fastening bolts 44 are drawn tight.

When my apparatus is used as a condenser in a refrigerating system, the cooling

water is admitted to the lower ends of the coils through the pipe 17 and after circulating upwardly through the coils, it is discharged through the pipe 37. The coils being of substantially equal length, the cooling liquid will be evenly distributed among them in its flow through the apparatus and the nesting of the coils made possible by their shape, as previously explained, enables them to be compactly arranged so that a maximum cooling surface is provided in a small amount of space. The carbonic acid gas, or other fluid to be cooled, is delivered through pipe 13 into the pipe 14 which projects upwardly to a point near the upper end of the casing 3 where it is provided with radially disposed perforations or openings 45 through which the fluid is discharged in a radial direction over and in contact with the surrounding coils. This distribution of the fluid over the coils enables the superheat of the fluid to be quickly absorbed and greatly expedites the cooling of the fluid, which flows downwardly over and in contact with the coils to the bottom of the chamber where it is collected. Since the cooling liquid flows upwardly in the coils and the liquid fluid to be cooled flows downwardly around the coils, it will be apparent that a counterflow between the cooling and cooled fluids is secured, which is most suitable to heat exchange and renders the apparatus highly efficient. The cooled fluid collected in the bottom of the chamber is delivered through the pipes 15 and 16 to an expansion valve or other point of use.

When the apparatus is to be used as a brine cooler, it is preferable to reverse the flow, and in this instance, the pipe 15 delivers the liquid carbonic acid through the perforations therein into the chamber around the coils where it is evaporated and flows out as a gas through the pipe 14, while the brine to be cooled flows downwardly through the coils in a counter-direction to the carbonic flow, the brine being delivered to the coils through the pipe 37 and from the coils through the pipe 17. Pipe 15 may also be provided with apertures to cause the delivery of the refrigerating medium radially therefrom and into contact with the surrounding coils. It should be obvious also that the refrigerating medium may be conducted through the coils and the brine or water as the case may be, may flow through the casing around the coils in a counter-direction to the flow of the medium. In order to provide for a reverse flow of a liquid through the coils for purposes of cleaning the same, the pipes 25 and 38 are connected by a connecting pipe 46 which enables the delivery of the cooling liquid, or of steam or other fluid into the upper ends of the coils for cleaning purposes when desired. To effect this result valve 29 is closed as is also

valve 30 in pipe 38, while valve 50 in pipe 46 and valve 28 in delivery pipe 27 are opened thus permitting the reverse flow through the coils.

- 5 My apparatus is designed to be operable under pressure without liability of leakage, and while containing tight joints at all points, is so constructed that it may be readily disassembled to permit access to the interior 10 of the cooling chamber whenever the same may be required. The coils are so constructed and arranged that they provide a maximum cooling surface in a minimum amount of space, thus providing a high 15 cooling capacity in a relatively small chamber, and the counterflow between the cooling liquids and the fluid to be cooled further facilitates the cooling action so that the apparatus is highly efficient in its operation.
- 20 It is believed that my invention and many of its inherent advantages will be readily appreciated from the foregoing without further description and while I have shown and described a preferred embodiment, obviously the details thereof may be varied within 25 considerable limits without departing from the essence of the invention as defined in the following claims.

I claim:

- 30 1. In a heat exchanging apparatus, the combination of a closed receptacle, a plurality of coaxially disposed cooling coils of substantially equal lengths arranged therein, means for distributing the fluid to be cooled over said coils, and an outlet from said receptacle.
2. In a heat exchanging apparatus, the combination of a closed receptacle, a plurality of internested coils of substantially equal 40 length arranged therein, a pipe extending upwardly from the bottom of said receptacle within said coils and having provision at its upper end for distributing the fluid to be cooled over said coils, and means for delivering the cooled fluid from the bottom of said receptacle.
3. In a heat exchanging apparatus, the combination of a vertically disposed closed 50 receptacle, a plurality of co-axially disposed coils of substantially equal length arranged within said receptacle, means for distributing the fluid to be cooled over said coils near the upper end thereof, and means for delivering the cooled liquid from the bottom of said receptacle.
4. In a heat exchanging apparatus, the combination of a vertically disposed closed 60 receptacle, a plurality of cooling coils nested together and co-axially disposed within said receptacle, said coils being of substantially equal length, headers connected to the upper and lower ends of said coils, means for distributing the fluid to be cooled over said

coils, and means for delivering the cooled fluid from the receptacle.

65

5. In a heat exchanging apparatus, the combination of a closed receptacle, coils comprising large and small portions arranged therein with the small portion of each coil nested within the large portion of another coil, said coils being of substantially equal length, headers connected with the ends of said coils, and means for delivering fluid to be cooled to said receptacle.

70

6. In a heat exchanging apparatus, the combination of a closed receptacle, three cooling coils disposed therein, one of said coils being of substantially equal diameter from end to end and the other coils each comprising a portion of larger diameter than the intermediate coil disposed around said intermediate coil, and a smaller portion disposed within said intermediate coil, headers connecting the ends of all of said coils, means for distributing fluid to be cooled over said coils, and means for discharging the cooled fluid from the receptacle.

80

7. In a heat exchanging apparatus, the combination of a plurality of coaxially disposed internested coils of substantially equal length, means for delivering a cooling medium through said coils, and means for delivering medium to be cooled over said coils.

85

8. In a heat exchanging apparatus, the combination of a cylindrical casing provided at its upper end with a removable cap, a plug forming the bottom of said casing, a ring shrunk onto the lower end of the casing, a pipe extending through said plug, a pipe extending through said cap, a plurality of coils disposed within said casing, and headers connected with said pipes and with said coils.

90

9. In a heat exchanging apparatus, the combination of a cylindrical casing provided at its upper end with a removable cap, a closure for the lower end of said casing, a plurality of coils disposed within the casing, a pipe extending through said closure and communicating with the interior of said coils, and inlet and outlet passages through said closure communicating with the interior of said casing around the coils.

105

10. In a heat exchanging apparatus, the combination of a closed receptacle, cooling coils arranged therein, supply and delivery pipes entering said chamber through the bottom thereof, supply and delivery pipes for said coils entering said chamber through the ends thereof, headers connecting said pipes with said coils, and a cross-connecting pipe connecting the aforementioned pipes through which the flow of the liquid in said coils may be reversed.
